(57) **CLAIM**

The ornamental design for a triaxial sensor, as shown and described.

DESCRIPTION

FIG. 1 is a perspective view from below, to the back and to the right side of a new design for a triaxial sensor;

FIG. 2 is an exploded perspective view from below, to the back and to the right side thereof;

FIG. 3 is a perspective view from above, to the front and to the left side thereof;

FIG. 4 is a perspective view from below and to the right side thereof;

FIG. 5 is a perspective view from above, to the back and to the right side thereof; and,

FIG. 6 is a front elevation view thereof.
